UNITED STATES PATENT OFFICE.

CHARLES G. MILLER, OF CHARLOTTE, NORTH CAROLINA, ASSIGNOR TO MCCLAREN RUBBER COMPANY, OF CHARLOTTE, NORTH CAROLINA, A CORPORATION OF DELAWARE.

DESIGN FOR A NONSKID-TIRE TREAD.

Application filed December 24, 1924. Serial No. 11,779. Term of patent 14 years.

To all whom it may concern:

Be it known that I, CHARLES G. MILLER, a citizen of the United States, residing at Charlotte, in the county of Mecklenburg and State of North Carolina, have invented a new, original, and ornamental Design for a Nonskid-Tire Tread, as shown in the accompanying drawing, forming part of this specification.

In said drawing:

Fig. 1 is an exterior face or edge view of part of the tire showing the peculiar bas-relief ornamental configuration thereof.

Fig. 2 is a transverse sectional view on the line 2—2, Fig. 1.

Fig. 3 is a transverse sectional view on the line 3—3, Fig. 1.

I claim:

The ornamental design for a nonskid tire tread substantially as shown.

CHARLES G. MILLER.
